UNITED STATES PATENT OFFICE.

GUSTAV A. BRACHHAUSEN, OF RAIHWAY, NEW JERSEY.

DESIGN FOR A COVER FOR MUSIC-BOXES.

SPECIFICATION forming part of Design No. 27,058, dated May 18, 1897.

Application filed April 1, 1897. Serial No. 630,304. Term of patent 14 years.

To all whom it may concern:

Be it known that I, GUSTAV A. BRACHHAUSEN, a subject of the German Emperor, residing at Rahway, Union county, State of New Jersey, have invented and produced a new and original Design for a Cover for Music-Boxes, of which the following is a full, clear, and exact description, reference being had to the accompanying drawings, wherein—

10 Figure 1 indicates a plan view of a design for a cover for music-boxes embodying my invention, and Fig. 2 is a side view of the same.

15 The essential features of my design for a cover for music-boxes consist in a base surmounted by a series of concave stepped portions surmounted by a convex cap.

Referring to the drawings, A indicates a base which is surmounted by a series of concave stepped portions *a*, the uppermost of which is shown as smaller in dimensions than that of the lowermost concave stepped portion. Surmounting the stepped portions *a* is a convex cap *b*, which is shown as surrounded by a beading *c*.

25

What I claim is—

The design for a cover for music-boxes, substantially as shown and described.

GUSTAV A. BRACHHAUSEN.
